UNITED STATES PATENT OFFICE

2,489,080

X-RAY TUBE COMPRISING A DISK-SHAPED ROTARY ANODE

Bart Combée, Eindhoven, Netherlands, assignor to Hartford National Bank and Trust Company, Hartford, Conn., trustee

Application July 18, 1947, Serial No. 761,965
In the Netherlands July 17, 1946

Section 1, Public Law 690, August 8, 1946
Patent expires July 17, 1966

2 Claims. (Cl. 250—148)

1

In screening by means of X-rays the time of examination must not be limited by the loading capacity of the X-ray tube as is the case in making exposures, when the X-ray tube is damaged upon exceeding the permissible loading time. In order to satisfy this condition it is required for the X-ray tube to remain operative practically continuously. For a short time after starting up the tube, the heat evolved by electrons impinging on the anode is mainly absorbed by the anode. As the temperature of the anode increases, an ever increasing quantity of heat is carried off until the average quantity of heat evolved per unit time and the heat carried off per unit time are ultimately equal. In using a tube having a rotary anode from which the heat evolved therein is carried off by radiation, the load is determined by the temperature of the anode, which must not exceed the maximum permissible value, and by the size of the radiating surface. Enlarging the surface of a disc-shaped anode, in order to increase the load, entails the disadvantage that the difficulties experienced in the manufacture of anode-discs increase as the diameter of the disc is larger. In this event, moreover, the internal strains of a rapidly rotating disc increase to such a degree that there is a risk of the production of cracks in the material. Finally, a large diameter of the disc influences the size of the tube, due to which the apparatus is bulky and has a higher weight, notably the tube is arranged in an envelope filled with oil.

X-ray tubes are known in which the anode-disc is in thermal relation, through a shaft, with a cooling member having a large surface and a high heat capacity, so that part of the heat produced in the anode is carried off and radiated by the cooling member at a comparatively low temperature. This cooling member is located in the tube where it surrounds the supporting members for the construction causing the anode to rotate so that great care has to be taken that the temperature of the said member remains below the temperature detrimental to the life of the said construction. It has been found that by this condition the heat transference from the anode to the cooling member is limited to at most 15% of the heat produced in the anode when the size of the rotor is to be kept within reasonable limits.

In another form of construction of an X-ray tube having a disc-shaped rotary anode the impact-disc for the electrons is provided on a disc consisting of refractory metal which is better workable than tungsten. This measure has for its purpose to increase the thermal capacity of

the anode but substantially not influence the heat emitting capacity.

However, this known construction permits of increasing the loading capacity of an X-ray tube having a disc-shaped anode which is adapted to be operated continuously. This fact is utilised by the invention which concerns an X-ray tube having a disc-shaped anode with which the impact-disc for the electrons is provided on a disc 10 consisting of nickel or other metal, the melting point of which is at least as high and which is better workable than tungsten. According to the invention the carrier-disc is provided with a rim having such a large heat radiating surface that at the maximum permissible temperature at least one third of the heat produced in the anode is carried off.

With rotary anodes it is known to provide the impact-disc for the electrons on a copper member. The low melting temperature of this metal constitutes an impediment to its use as a thermal emitter. Along this path heat is carried off even during operation, it is true, but the thermal emission is small relatively to the supply of heat, 25 so that the member acts as a heat container, the operation having to be interrupted as soon as the maximum permissible temperature is reached.

In using metals having a higher melting point the thermal radiation obtained at a high temperature increases the dissipation of heat, so that a heat container can be dispensed with and the tube can be operated for a longer time.

In order that the invention may be clearly understood and readily carried into effect it will 35 now be explained more fully with reference to the accompanying drawing in which an X-ray tube according thereto is represented in part diagrammatically.

In this drawing the reference numeral 1 denotes the glass bulb surrounding the cathode 2 and the anode 3. The bulb and the cathode are represented diagrammatically and may be of conventional construction.

The anode comprises two parts interconnected by the shaft 4, one part receiving the beam of electrons emitted by the cathode, and the other part comprising a rotary construction. The anode is supported by ball bearings 5 which are secured to the stationary shaft 6 and connected to the rotor. The latter consists of a copper jacket 7 provided with a lining 8 which consists of iron for the electromagnetic driving. The jacket carries the shaft 4 and the tungsten 55 anode-disc 9 which is provided on a disc 10 con-

sisting of metal which is better workable than tungsten, this disc having a rim 11.

Through the contact surface between the anode-disc 9 and the carrier plate 10 a quantity of heat passes to the latter. The temperature to which the plate 10 can be heated depends upon the metal from which it is made. This temperature should not be exceeded during operation.

Suppose that the disc-anode has a working temperature of 1500° K.; the specific thermal radiation then being 6.5 watt/sq. cm. for tungsten. The temperature of the carrier plate may, for instance, be 1200° K.; this plate may consist of molybdenum or even of iron, the specific radiation for a well blackened surface then likewise being 6½ watt/sq. cm. When the tube is to be loaded with 500 watt, half of which is radiated by the anode, whereas the other half is carried off to the carrier plate and, by the shaft, to the rotor, the disc-anode requires a surface of

$$\frac{250}{6.5} \approx 40 \text{ sq. cm.}$$

the diameter consequently being 50 mms.

In order that the ball bearings should not be affected by the heat, the temperature of the rotor must not exceed 600° K. the radiation coefficient of a blackened copper surface of 100 sq. cm. is approximately 2.95×10^{-10} . The thermal emission is proportional to the radiation coefficient and the fourth power of the temperature, whence it follows that the emitted quantity of heat $E = S_2 T^4$ is equal to 39 watts. Consequently, the carrier member has still to radiate 211 watts which means that the radiating surface must approximately be

$$\frac{211}{6.5} = 33 \text{ sq. cm.}$$

In the event of a diameter of 4 cms. the rim has a height of 24 mms.

In the absence of the carrier member the anode-disc, in order to be able to withstand the same load, must have a surface of

$$\frac{500 - 39}{6.5} = 71 \text{ sq. cm.}$$

and a diameter of 67 mms.

In a very advantageous construction the carrier-disc consists of titanium iron which is provided with a black surface obtained by oxidation. The relation between the black layer and the metal surface is not appreciably affected when the carrier-disc is heated to incandescence, so that, in

contra-distinction to other metal surfaces blackened in the same manner, a permanent improvement of the radiation coefficient is obtained.

When making use of the invention an X-ray tube employed for screening and having a disc-shaped rotary anode can be loaded with impunity to a degree 50% higher than it was possible in the past. When providing the rim with apertures for reducing the weight of the carrier-disc and its moment of inertia this improvement is not appreciably affected.

What I claim is:

1. An X-ray tube having a rotating anode comprising an anode disc of tungsten, and a supporting disc of titanium iron provided with a black oxidized surface, said supporting disc being provided with a rim portion having a surface area for radiating at least one-third of the heat produced in said anode disc when said anode disc is operated at the maximum operating temperature.

2. An X-ray tube having a rotating anode comprising an anode disc of tungsten, and a heat-radiating cup-shaped supporting member for the anode disc of black oxidized titanium-iron provided with a plurality of apertures in the rim portion thereof, the rim portion having a surface area for which at least one-third of the heat produced in the anode disc at the maximum operating temperature thereof is radiated from the supporting member.

BART COMBÉE.
